UNITED STATES PATENT OFFICE

HAROLD B. WOODS, OF ILION, NEW YORK, ASSIGNOR, BY MESNE ASSIGNMENTS, TO
REMINGTON SERVICE MACHINES, INC., A CORPORATION OF NEW YORK

VENDING MACHINE

Application filed December 27, 1927. Serial No. 242,579.

This invention relates to vending machines and particularly to the type of machine adapted to contain a number of similar articles and to deliver one such article at a time upon the operation of the machine following the insertion of a proper and acceptable coin.

One object of the invention is to provide a machine of unusual capacity. Hitherto it has been possible to load such a machine only with a very limited number of the articles to be vended unless the casing of the machine was made of excessive height. By the present invention it is possible to load a machine 15 contained in a comparatively small and low casing with an unusually large number of the articles to be vended.

A further object of the invention is to provide a novel and effective means for effecting 20 the release of the machine for operation by an accepted coin.

A further object of the invention is to provide means for preventing the acceptance of a second coin, one coin being in position to 25 operate the machine, until the machine has been operated.

A further object of the invention is to provide a novel means for effecting the return of superfluous or spurious coins or slugs upon 30 an initial movement of the mechanism and without a complete operation of the machine.

A further object of the invention is to provide an article ejecting device which is positively actuated both to eject an article and 35 to return to normal position.

A further object of the invention is to provide a plurality of stacks of similar articles, each stack having an ejector device associated therewith and means for operating the 40 ejector devices in rotation.

A further object of the invention is to provide a novel means for effecting the return of inserted coins after the stock of articles in the machine has been substantially ex- 45 hausted.

A further object of the invention is to provide an operating device for a vending machine which includes a connection adapted to yield without injury to the mechanism 50 when excessive force is applied to the op-

erating device while the machine is locked or accidentally jammed.

With these and other objects in view, the invention consists of the novel combinations and arrangements of devices, a representative embodiment of which is shown in the accompanying drawings, and which will be hereinafter described in detail.

Fig. 1 is a front view of the machine enclosed in its case.

Fig. 1A is a transverse sectional detail showing the casing supporting means.

Fig. 2 is a front elevation of the machine, the front wall of the casing being removed.

Fig. 3 is a rear elevation of the mechanism, the casing being removed.

Fig. 4 is a section on the line 4—4 of Fig. 2.

Fig. 5 is a transverse section substantially on the line 5—5 of Fig. 6.

Fig. 6 is an elevation in section substantially on the line 6—6 of Fig. 5.

Fig. 7 is an elevation of the main operating shaft and parts associated therewith.

Fig. 8 is a section on line 8—8 of Fig. 7.

Fig. 9 is a detail of a pair of delivery mechanism operating cams.

Fig. 10 is a perspective of the delivery mechanism and its operating cams, some parts being omitted for the sake of clearness.

Fig. 11 is a transverse section near the top 80 of the machine.

The mechanism is enclosed in a casing comprising front, side, and end plates; and is mounted on a back plate 15 to which the housing is attached in the following manner:

Near the top of the back casing plate is secured a yoke comprising a transverse bar 16, secured to the back, and forwardly extending arms 17 having inclined slots 18 near their forward ends, as shown in Fig. 1A. 90 The side walls of the housing are provided with a pair of inwardly projecting studs 19 adapted to be received in slots 18. Near the bottom of the back plate 15 is secured a stirrup 20 (Figs. 5 and 6) which comprises a key hole slot 211 adapted to receive the end of a spindle 22 and a lug 21 which projects laterally therefrom. Spindle 22 is supported in the mechanism framework to be presently described, extends forwardly to a point adja- 95 100

cent the front wall of the casing, and at its forward end carries the locking plate 221. Plate 221 is provided with the locking projection 222 adapted in one position of the plate to engage beneath end of a locking piece 223, secured to the inside of the front wall of the casing. Plate 221 is urged to unlocking position by spring 224, which tends to draw it into contact with the stop pin 225. Its movement to locking position is effected thru the engagement of a tooth 226 thereon by a nose 227 on the bolt of a lock 23, secured to the casing. Thus, the casing being in place, a key is inserted in this lock and turned to bring the nose 227 to the position shown in Fig. 1, plate 221 is rotated to bring nose 222 under the end of locking piece 223 and the casing is securely locked in place. A locating stud 228 on the inside of the front casing plate is received in an opening 229 in the mechanism frame, thus properly aligning the casing and parts carried thereby with the corresponding parts of the mechanism.

The mechanism for containing articles to be vended and for delivering such articles, one at a time, upon the insertion of a proper coin, is supported on a unitary frame work comprising a base casting 24 (Fig. 2) having secured thereto a back plate 240 integral with a right side plate 241. A mechanism supporting plate 242, (Fig. 3) lying parallel to the back plate 240 and spaced therefrom by means of lugs 25, partly overlaps and extends below the back plate 240. The upper end of plate 240 is offset rearwardly, as shown at 243, (Figs. 2 and 4) and the offset portion comprises slots adapted to receive headed studs 244 secured to the back plate 15. The lower end of plate 240 rests against the stirrup 20 and is held in place by the lug 21 of locking bolt 22.

The article supporting means comprises a plurality of columnar bins or holders 26 each of a cross sectional area substantially the same as the cross sectional area of the articles to be vended. Each bin thus receives a single column of such articles. Each of the stacks of articles is supported on a shelf which is constructed as follows:

A shelf base 28 is provided with a downwardly turned end 29 by which it is secured to the back plate 240. At one edge, the base is turned upward and backwardly to form the support or shelf proper 30 upon which the articles rest. Each shelf 30 comprises slots 31 (Figs. 5 and 6) adapted to receive the ejector stirrups 32. The right side wall (Fig. 2) of each of the bins 26 is somewhat shorter than the left side wall to permit of the ejection beneath the right side wall of the bottom article in the stack. The left-side walls each comprise slots 33 (Fig. 5) thru which the ejector stirrups 32 are reciprocated. Each of the bins may be provided with a weight device 34 resting on top of the

stack of articles for the purpose of insuring that articles do not become lodged in the bins out of the path of movement of the supports 31.

Means may be provided for locking the machine or returning all coins inserted therein when the machine is empty, the operation of this mechanism being initiated by the position of one or more of followers 34. A gravity operating device has been shown associated with each follower, in order to lock the machine when any of the bins becomes empty. The three devices are identical, each comprises a yoke pivoted on a rod 35 which extends transversely between the upstanding walls of the follower 34. The yoke comprises a downwardly extending finger 36 and an upwardly extending arm 37 connected by a transverse bar 38. The arm 37 and the bar 38 being above and to the left (Fig. 6) of the pivot 35, the end of arm 37 normally rests against the back of the bin 26 where said back lies adjacent to the back supporting plate 240. When the last article in the bin is removed the finger 37 comes into alignment with aligned slots 39 thru the wall of the bin 26 and the back plate 240, drops thru said slots and projecting from the back of the plate 240, acts to effect the return of subsequently inserted coins in a manner which will presently be described.

Coins are inserted in the machine thru a slot 40 in an escutcheon plate 41, mounted on the front of the casing. In alignment with the slot 40 is a coin testing device comprising a fixed wall 42 having hinged thereto a swinging wall 421. When wall 421 is swung aside, coins lodged in the testing device or thereafter introduced into the machine drop into the open receptacle for delivered articles, from which they may be recovered. The coin testing device will not be described in detail since it forms no part of the present invention. The wall 421 being in normal position, the accepted coins passing thru the coin tester drop into a vertical chute 43 secured to the rear of the back support plate 240. At the bottom of this chute the coin comes to rest with its lower edge in contact with an arm 44 of a three arm lever pivoted to the plate 240 at 45. Both walls of the coin chute comprise vertical slots opposite the position occupied by the coin in the lower end of the chute. Thru the left-hand slot (Fig. 3) projects the lower end of a light lever 46, pivoted on a horizontal pivot at 47. This lever comprises an inturned upper end 48 adapted to be projected thru a slot near the upper end of the coin chute 43 and when in this position to engage inserted coins and retain them in the coin tester, from which they are dislodged by the opening of the tester on a subsequent operation of the machine. Thus, when there is a coin in the bottom of the chute 43 in position to operate the ma-

chine no other coin will be accepted, and if an attempt is made to insert another coin in the machine the coin will be returned.

Thru the slot in the right-hand side of the lower end of coin chute 43 projects a nose 49 of a sliding and rocking lock member 50. The movement of this member is guided by a slot 51 which receives a stud 52 projecting rearwardly from the mechanism supporting plate 242 and by a slotted stud or guide plate 53 also secured to the plate 242. Pivoted to the lock controlling member 50 at 54 is a locking plate 55 having therein a laterally projecting stud 56 which overlies a horizontally extending portion of the member 50, and a similar stud 57 which is engaged by the nose of a spring connecting member 58 urged into contact with said pin by spring 59. Member 58 thus serves to apply the tension of spring 59 to the stud 57 and the lock controlling member 50. A short stud 60 fixed to the plate 242 limits the movement of the locking plate 55 in a manner which will presently appear.

Plate 55 comprises a locking corner or shoulder 61 adapted to be engaged by radial locking projection 62 on a disk 63 fixed to the operating shaft 64. The disk 63 also carries three laterally projecting studs 65 adapted to engage the nose 66 of the lock controlling member 50 and lift said member and with it the plate 55, rocking it about the stud 52. The lever 451 comprises a horizontally extending arm 67 which engages the periphery of a three lobed cam 68, fixed to the operating shaft 64 adjacent to the disk 63. Lever 451 also comprises an upwardly extending part terminating in the laterally projecting finger 681 adapted to engage a pin 69 associated with the swinging side 421 of the coin chute; and an arm 70 terminating in a bifurcation adapted to receive a pin 71 which projects from a pendant 72 pivoted to the plate 240. Pendant 72 comprises three extending fingers 73 which normally stand opposite the slots 39 thru which the fingers 37 on the followers 34 are projected when the bins are empty as hereinbefore explained. It will be seen that at each operation of the machine, the lever 451 being rocked by the engagement of cam 68 with arm 67, the fingers 73 are moved out of alignment with the slots 39 and at the same time the hinged side of the coin chute is lifted and remains elevated as long as fingers 73 are displaced. If the operation empties one of the bins 26 permitting a finger 37 to drop thru one of the slots 39, the return movement of the pendant 72 is blocked and the coin chute is held open thus effecting the return of any coins subsequently placed in the machine.

The invention contemplates the delivery of an article from each of the three stacks in turn, and to this end the delivery mechanism may be constructed as follows:

The ejector stirrups 32 are carried by plates 321, 322, and 323 respectively (Fig. 5) which extend horizontally from the upper ends of levers 74, 76, and 78, pivoted respectively on the rods 75, 77, and 79. For greater rigidity, 70 the lower end of each lever is formed as a yoke, thereby providing spaced bearing points (Fig. 10). The yoke of lever 74 is widened into a plate 741 which forms one side of the operating mechanism housing. 75

For positively controlling the article delivery levers 74, 76, and 78, two pairs of complemental cams are mounted on the operating shaft 64. These pairs of cams are similar, one pair serving to control the delivery levers 74 and 76 and the other to control the lever 78. A pair of these cams is shown detached from the mechanism in Fig. 9, and they are shown in their relation to each other, as well as to the arms operated thereby in 80 Figs. 7, 8, and 10. Suitable cam followers project from the three delivery levers to engage their cams, thus the arm 74 is provided with a stud 80 which engages the periphery of the cam 81, and with a second stud 82 which 90 engages the periphery of a cam 83 which is complemental to the cam 81. Thus, the delivery lever is positively actuated in both directions. Similarly, lever 76 is provided with the cam followers 84 and 85 which engage respectively the cam 81 and its complemental cam 83, while the lever 78 has the followers 86 and 87 which engage respectively a second pair of complemental cams 88 and 89. 100

The arrangement of the cams and cam followers and their relation to each other is such that each of the delivery levers is actuated in turn while the main operating shaft 64 is turned thru one complete revolution, the operation of each lever being effected during one-third of a revolution. It will be seen that about two-thirds of the periphery of each cam is a dwell portion, the active surfaces being limited to about one-third of a circumference. In Figs. 8 and 9, the mechanism is so positioned that the lever 74 will be actuated during the rotation of the operating shaft thru the next third of a revolution, said shaft rotating clockwise. The lever 74 is in normal position, the delivery stirrup 32 standing adjacent to the article containing bin as shown in Fig. 5. The lever 76, controlled by cam followers 84 and 85 was actuated in the preceding movement of the shaft, and said cam followers stand just behind the active cam surfaces. As the shaft 64 and with it cams 81 and 83 are rotated clockwise from the Fig. 9 position, the follower 82 will be engaged by the extending part of cam 83, rocking the lever 74 about its pivot 75 to eject the bottom article in the stack. This movement is permitted by the recess in the periphery of cam 81 which receives the follower 80 while the lever is 110 115 120 125 130

rocked thru the engagement of cam 83 with follower 82. In the continued movement of the cams, follower 82 passes the point of cam 83 permitting cam 81 to restore the lever to normal position thru its action on the follower 80. Throughout this and the succeeding cycle, cam followers 84 and 85 are stationary. After rotation thru one-third of a revolution, the further movement of the mechanism is blocked until again released by the insertion of a proper coin as herein-after explained. During the succeeding one-third of a revolution, followers 80 and 82 also remain stationary, and cams 88 and 89 act on the followers 86 and 87 associated with the lever 78 to actuate this lever to deliver an article and subsequently restore it to normal position. During the third operation, both levers 74 and 78 are held idle, lever 76 being actuated and restored by the action of cams 81 and 83 on its followers 84 and 85.

Retrograde movement of the operating shaft 64 is prevented by means of a pawl 90 which is drawn by spring 91 into engagement with the teeth of ratchet wheel 92 fixed to the shaft 64. At three positions spaced 120° apart, one tooth of the ratchet wheel 92 is omitted, as indicated at 93, to permit the return of the mechanism to normal position after a displacement thereof which is sufficient to operate the mechanism herein-before described to open the coin tester and drop any articles contained therein. Movement of the mechanism sufficient to cause pawl 90 to engage the tooth of the ratchet wheel adjacent to the blank spaces 93 is blocked in the absence of an accepted coin in the bottom of the passage 43 as will be presently explained.

The machine is operated by a manipulative device associated with the main shaft 64. In order to prevent injury to the mechanism by the application of excessive pressure when the machine is locked, a friction drive device is provided.

The operating member comprises a finger piece 94 which extends transversely of and projects from a disk 96 having a recess 97 in its inwardly facing side. The disk 96 is rabbeted to receive the margin of flange 95 of an apertured escutcheon plate 98, secured to the case. The disk 96 is rotatably secured to the escutcheon by an apertured plate 99 which extends over the flange 95 and is suitably secured to the disk. The aperture in plate 99 receives a cylinder 100 having an axial recess 101 adapted to receive the end of shaft 64. Motion is transmitted from cylinder 100 to shaft 64 by means of a cross pin 102 in the cylinder, which is engaged by the forked end of shaft 64.

A washer 103 encircles the cylinder 100 and is held between the plate 99 of the finger piece disk 96 and an end plate 104 secured

to cylinder 100. A second washer 105 encircles the cylinder 100 on the opposite side of the plate 99, and a stiff spring 106 is compressed between this washer and an abutment at the opposite end of the cylinder. Thus, when the finger piece 94 is rotated the motion of plate 99 secured thereto is transmitted frictionally thru the washer 103 to the end plate 104 of cylinder 100, thence by cross pin 102 to shaft 64. However, if for any reason the resistance of shaft 64 to rotation is excessive, plate 99 will slip on washer 103. Thus, injury to the mechanism by the application of excessive force to the finger piece when the machine is locked is obviated.

The operation of the machine is as follows:

The coin must first be inserted in the machine, accepted by the coin tester and advanced to the bottom of the chute 43 where it rests upon the lever nose 44. If an attempt is made to operate the machine without a coin in this position, the initial movement of the engagement of the shoulder 61 with lug 62, cause the lock release member 50 to move transversely. The rocking plate 55 which is pivoted to member 50 moves transversely with said member, rotation thereof being prevented by the engagement of the inclined nose of spring connecting member 58 with the stud 57. Such transverse movement continues until the edge of rocker 55 engages the fixed stud 60, positively locking the mechanism against further movement. The initial movement permitted by the clearance between the rocker 55 and stud 60, however, is sufficient to cause the cam 68 to lift the lever nose 67 and effect the opening of the coin tester thru the engagement of nose 681 with the projection 69 on the hinged side of the coin tester.

When a coin is in the bottom of chute 43, the longitudinal movement of the lock releasing member 50 above described is blocked by the engagement of nose 49 with the face of the coin. In this condition, lug 62 pressing against the shoulder 61 will rotate the plate 55 against the tension of spring 59 and movement of the disk 63 brings one of the studs 65 into engagement with the inclined nose 66 of member 50 and rocks this member about the stud 52. Plate 55, being pivoted to the member 50, is thus lifted and shoulder 61 is disengaged from lug 62 permitting disk 63 to rotate until the next succeeding lug 62 again engages the shoulder 61. During this movement, the lever 451 is rocked by the engagement of nose 67 with cam 68 withdrawing the nose 44 from the end of the coin chute and permitting the coin which has operated the machine to drop into the coin receptacle 110. Lock releasing member 50 will be retracted out of engagement with the coin by a spring 59 as soon as the nose 66 has passed

the stud 65. The accepted coin on dropping to the bottom of the chute 43 rocks the lever 46, projecting the nose 48 into the top of chute 43 and retaining any coins thereafter tendered in the coin tester to be returned on the initial movement of the operating mechanism.

The rotation of shaft 64 thru one-third of a revolution in the manner above described will effect the operation of one of the ejectors, the other two ejectors remaining stationary. Upon a second operation of the machine, another of the ejectors will be operated, and upon the third operation the remaining ejector will be operated, the three ejectors being actuated in rotation on successive operations of the machine and only one ejector being moved at any one operation. When the stock of articles in any one of the bins 26 has become exhausted, the arm 37 associated with such bin will be projected thru the slot 39 and will block the return to normal position of the pendant 72, thus retaining the coin tester open and preventing the acceptance of any coin until the machine is recharged.

When the machine is to be recharged and the collection of coins removed, the proper key is inserted in the lock 23, and bolt 22 is turned to withdraw lug 222 from under the end of lock plate 223. The bottom of the casing can then be drawn outwardly, withdrawing the cross pin 102 from the slotted end of shaft 64. The casing can then be lifted to remove studs 19 from their slots 18 in arms 17 and the casing completely removed, rendering the bins 26 and the coin box 110 accessible. If repairs to the mechanism are necessary, by means of plate 221 the spindle 22 may be rotated to bring the laterally extending lug 21 into alignment with the slot in stirrup 20, permitting the lower end of the mechanism frame to be moved forward, with drawing lug 21 thru its slot. The mechanism frame can then be removed from the back by lifting it until the studs 244 pass out of the slots in plate 243.

The invention is not to be considered as limited to the specific devices which have been illustrated and described but is to be construed as extending to all equivalent mechanisms falling within a broad interpretation of the appended claims.

55 What is claimed is:

1. A vending machine comprising a plurality of receptacles adapted to receive stacks of similar articles and delivery mechanism associated therewith adapted to remove articles from said stacks in rotation, said delivery mechanism comprising a common operating member, ejector devices, and trains of inelastic mechanical elements connecting said common member with said ejector devices whereby said devices are positively actuated

to remove an article and positively restored to normal position.

2. In a delivery mechanism for vending machines, an ejector lever, a main operating shaft, an operating finger piece in alignment with and effective to rotate said shaft, complementary cams on said operating shaft and cam followers associated with said ejector lever adapted to engage said cams.

3. In a delivery mechanism for vending machines, an operating shaft, a pair of complementary cams fixed to said operating shaft, a plurality of ejector levers and cam followers associated with said ejector levers and engaging said pair of complementary cams, the arrangement of said followers being such that each ejector lever is actuated and restored to normal position while the remaining ejector levers are idle.

4. In a delivery mechanism for vending machines, a main operating shaft having mounted thereon a locking disk, a coin mechanism controlling cam, a pair of complementary cams, and a ratchet device for preventing retrograde movement of said shaft, in combination with devices co-operating with said disk, said cams and said ratchet device.

5. In a delivery mechanism for vending machines, an operating shaft having mounted thereon a plurality of pairs of complementary cams and a plurality of ejector devices controlled by said cams, the number of ejector devices thus controlled being greater than the number of pairs of the controlling cams.

6. In a coin controlled device, a sliding and rocking lock controlling member having a lock engaging element pivoted thereon, a lock engaged by said element and tending when actuated to rock said element about its pivot, means whereby the lock controlling device is moved bodily on such engagement and means whereby preventing the bodily movement of said lock controlling member effects the release of the lock.

7. In a coin controlled device, the combination of a locking device, a contacting locking device, a lock controlling member on which said contacting locking device is movably mounted, said member being adapted to be moved bodily in the absence of a coin to lock the mechanism after a short initial movement thereof, and means operative on said controlling member independently of said contacting locking device to rotate said member to lock releasing position when its bodily movement is blocked by the presence of a coin.

8. A coin controlled device comprising a coin tester, a chute adapted to receive coins accepted by said tester, means for retaining coins in said chute in mechanism controlling position, means whereby the presence of a coin in said position prevents the passage of a second coin from said tester into said chute, and means associated with said coin retain-

ing means for opening the coin tester to discharge any coin thus retained therein.

9. In a vending machine, receptacles for a plurality of stacks of articles to be vended, followers for said articles, coin controlled means for delivering articles from said receptacles in rotation on successive operations of the machine, and means mounted on said followers for effecting the return of all coins inserted in the machine after the supply of articles in any one of said receptacles has become exhausted.

10. In a vending machine, a coin testing device adapted to be opened to discharge articles lodged therein, a coin chute adapted to receive coins accepted by said tester and retain them in mechanism controlling position, an article receptacle means controlled by the exhaustion of the supply of articles in said receptacle comprising a pendant, an operating mechanism, and a unitary member controlled by said operating mechanism and adapted to oscillate said pendant, open said coin tester, and effect the discharge of the coin in the coin chute.

11. In a delivery mechanism for vending machines, an operating shaft having mounted thereon a pair of complementary cams, and a plurality of ejector devices adapted to be actuated one at a time by said pair of cams.

12. A vending machine comprising a back plate, a unitary mechanism supporting frame adapted to be secured to said back plate, vending mechanism mounted in said frame comprising an operating shaft, a casing, casing locating and supporting devices mounted on said back plate, a finger piece mounted on said casing, and connecting means associated with said finger piece adapted to establish an operative connection with said operating shaft when said casing is placed in said casing supporting device.
